UNITED STATES PATENT OFFICE

STANLEY A. CRANE, OF NORWOOD, OHIO, ASSIGNOR TO THE HENNEGAN COMPANY, OF CINCINNATI, OHIO, A CORPORATION OF OHIO

ADVERTISING DISPLAY DEVICE

Application filed December 10, 1931. Serial No. 580,050.

The invention relates to display devices adapted to be attached to containers of salable merchandise.

Heretofore, considerable difficulty and expense has been experienced by manufacturers, who pack their product in containers, in satisfactorily and attractively displaying the product within the containers. If the containers are formed from transparent material, such as glass, the product confined within the containers usually has a different and more attractive appearance when poured therefrom into another container, such as a cup or tumbler. For this reason, display of the product in the original containers is not sufficiently appealing to the prospective purchasing public to justify great expense or trouble either on the part of the manufacturer or retail dealer. On the other hand, a product which is confined within an opaque container cannot be observed by prospective purchasers, unless the container is opened which results in the product soon becoming deteriorated or soiled thereby necessitating throwing away or otherwise disposing of both the container and its contents without much usage or advantage. This is an expensive procedure, particularly in localities where the product quickly deteriorates or becomes soiled.

Therefore, the objects of the invention are to provide a simple, economical and durable display device adapted to be quickly and conveniently attached to containers of salable merchandise; to provide a device for effectively and economically displaying and advertising salable merchandise or other commodity; to provide a device of this character formed from paper, or other suitable fibrous sheet material, and so constructed that said device may be packed and shipped in sheet formation and afterward manually bent conveniently for the purpose of forming a display device; to provide a device adapted for use in displaying or illustrating the contents of packages without necessity of opening said packages; and to provide a display device having adjustable means for the purpose of enabling users to adjust the device to various kinds and different sizes of containers.

The invention consists in the combination and arrangements of the parts, in details of the construction of said parts, and other features hereinafter made apparent by description and claims.

In the drawing.

Fig. 1 is a side elevational view of a bottle having incorporated therewith the invention, and showing a front elevational view of the invention;

Fig. 2 is the same showing the invention in vertical section;

Fig. 3 is a plan view of the invention in flat or unfolded formation;

Fig. 4 is a section taken on a line corresponding to 4—4 in Fig. 2;

Fig. 5 is a side elevational view of a modified form of container showing a modified form of the invention attached thereto;

Fig. 6 is a plan view of the modified form of the invention with parts broken away; and

Fig. 7 is a plan view of a modified form of a fastener.

The preferred construction of the invention 75 is exemplified or attached to the usual near-beer bottle, or transparent container 1', having the usual neck 2 integral with the usual cylindrical body 3. The bottle is sealed by the usual crown 4 fixed to the top of the neck 2.

In the preferred construction of the invention the vertical and upwardly extending apron 5 has its lower edge 6 integrally formed with the rectangular strip or band 7 having the spaced apart slots 8 formed in its end 9. 85 Integrally formed with the end 10 of the strip 7 is the narrow tongue 11 adapted to be received in any of the slots 8.

Painted or drawn upon the fronts 12 and 13, respectively, of the apron 5 and the strip 7 is a painting 3' which is a representation of the upper portion of a glass having near-beer, or other liquid forming a foam, therein and exposed to the air.

For the purpose of displaying a representation of a glass, or tumbler, full of near-beer, without opening the bottle 1', the band 7 is placed around the body 3 of the bottle, as shown in Fig. 1, with the inner surface 14 of the apron 5 in vertical alignment with the

outer surface of the body 3, as shown in Fig. 2. The tongue 11, as shown in Fig. 4, is passed inwardly through one of the slots 8; then outwardly through another one of the slots 8; and the outer end 15 of the tongue 11 is manually forced outwardly so that the tongue 11 slips through the slots thereby tightening the band 7 around the body 3 of the bottle 1'. As to which slots the tongue 11 is passed through depends upon the size of the body 3 of the bottle.

Intermediate the lower edge 6 of the apron 5, and the upper edge 16 of the strip 7 are the cuts 17 and 18 adjacent and below the side edges 19 and 20 of the apron whereby, when the strip 7 is tightened around the circular body 3 of the bottle, the lower edge of the apron, adjacent the cuts 17 and 18, extends outwardly as shown in Fig. 1, instead of being bent to conform to the shape and contour of the bottle.

The purpose of permitting the side edges 19 and 20, of the apron 5, to extend outwardly from the bottle is to provide a relatively large space, when viewed from the front, on the apron 5 to permit being printed thereon the character 21, which may be a notification of the quantity or quality of the product, name of the manufacturer and product, and other desirable information. Another purpose in having the side edges 19 and 20, of the apron 5, extend from the bottle 1' is to render realistic effect to the picture, or painting 3'.

The lower edge 22 of the strip 7 represents the line between the upper surface of the liquid and the lower surface of the foam which usually forms on near-beer in a tumbler. The space between the edge 22 and the horizontal line 16', on the strip 7, represents the portion of the tumbler above the liquid near-beer and below the foam 23 which usually extends above the upper edge, represented by the line 16' of the tumbler.

When viewing the bottle 1' and the invention 1 from the front a prospective purchaser, or other person, immediately sees the character 21, which may express the message of a manufacturer to a prospective purchaser. The prospective purchaser also sees the lower part of the body 3 of the bottle 1', in combination with the painting 3', which simultaneously conveys to him a mental picture of the product within the bottle as it appears after it is poured into a tumbler, thus the product within the unopened bottle appeals to the observer in a manner adapted to influence or induce him to purchase the bottle 1' and its contents.

A modified form of the invention is shown in Fig. 5 in which the usual closed fibre, or paste-board, container 24 has fixed to its top the band 7' having integrally formed with its upper edge the apron 5'.

On the front of the apron and band is the

painting 21' which is a representation that the top of the container 24 is open and the contents, which in this instance is soap flakes, or like substance, is heaped therein and exposed to the air. The character 21'' is printed upon the apron 5' and may consist of a notification from the manufacturer of the soap flakes, the name and address of the manufacturer, or other desirable information.

The band 7' has integral with one end the tongue 11' adapted to be received in the slots 8' for the purpose of retaining the band and apron on the container 24. The cuts 17' and 18', between the upper and lower edges, respectively, of the band and apron, permit the outer ends or edges of the apron to extend outwardly from the container 24.

A modification of the fastener is shown in Fig. 7. The band 25 has ends 26 and 27, in the upper and lower edges of which are the slots 28 and 29. When fastening the band 25 to a container the slots 28 and 29 are placed adjacent each other and the ends 26 and 27 of the band are manually forced toward each other whereby the ends are secured together.

An advantage of the various forms of the invention is that they are economical to manufacture and, being in sheet formation, a plurality of said devices can be packed and shipped compactly in a relatively small space, thus conserving the cubical area of the cartons or other containers in which the devices are packed for shipment or storage, whereby the transportation and storage costs are reduced to a minimum.

Another advantage of the invention is that prospective purchasers and observers are instantly attracted by the unique appearance of the invention, in combination with the container of a product, whereby the manufacturer is successfully enabled to convey to such observers desired information regarding the appearance of his salable product.

Still another advantage of the invention is that one size thereof is adapted, because of adjustability of the tongues 11 and 11', shown in Figs. 3, 4 and 5, in the slots 8 and 8', to fit various different sizes of containers. The modification shown in Fig. 7 also is adjustable.

It is, therefore, apparent that I have invented a highly desirable device of the character described and for the purposes intended, which is readily adaptable for use in displaying various articles and commodities.

It is, of course, understood that the display devices may be made of any size, and constructed of any materials deemed convenient and suitable for a device of this character. While I have illustrated and described forms of construction, and arrangements of the elements and parts, such as the means for adjustment, which I have found

desirable in materializing the invention, yet I wish to emphasize the fact that I desire to include in this application all equivalents and substitutes that may fairly be considered to come within the scope and purview of the invention as defined in the claims.

What I claim as new and desire to secure by Letters Patent is:

1. A display device formed from sheet material and comprising a band having slots in one end and having a tongue on its other end, an apron integral with the upper edge of said band and extending upwardly, said apron having thereon a representation of merchandise exposed to air, whereby when said band is placed around a container of merchandise and said tongue is received in said slots and said device is secured to said container it appears that said merchandise within said container is exposed to air.

2. A display device formed from sheet material and comprising a band, an apron integral with the upper edge of said band and extending upwardly, said apron having thereon a representation of merchandise exposed to air, whereby when said band is placed around a container of merchandise and secured to said container it appears that said merchandise within said container is exposed to air.

3. The combination with a container adapted to contain salable merchandise, of a display device comprising a band having spaced apart slots in one end adapted to receive the other end of said band, an apron integral with the upper edge of said band and having on its front a representation of the top of said merchandise, whereby when said band is received around said container, and one end is received in said slots, said apron is attached to said container for the purpose of forming a display representing that the top of said merchandise within said container is visible, said device having cuts at its side edges and intermediate said band and said apron, whereby the outer side edges of said apron are adapted to extend outwardly from said container.

4. The combination with a container adapted to contain salable merchandise, of a display device comprising a band, an apron integral with the upper edge of said band and having on its front a representation of the top of said merchandise, whereby when said band is received around said container said apron is attached to said container for the purpose of forming a display representing that the top of said merchandise within said container is visible, said device having cuts at its side edges and intermediate said band and said apron, whereby the outer side edges of said apron are adapted to extend outwardly from said container.

5. The combination with a container adapted to contain salable merchandise, of a

display device comprising a band having spaced apart slots in one end adapted to receive the other end of said band, an apron integral with the upper edge of said band and having on its front a representation of the top of said merchandise, whereby when said band is received around said container, and one end is received in said slots, said apron is attached to said container for the purpose of forming a display representing that the top of said merchandise within said container is visible.

6. The combination with a container adapted to contain salable merchandise, of a display device comprising a band, an apron integral with the upper edge of said band and having on its front a representation of the top of said merchandise, whereby when said band is received around said container said apron is attached to said container for the purpose of forming a display representing that the top of said merchandise within said container is visible.
